Primary Examiner — Wan Laymon*Assistant Examiner* — Mark Booker(74) *Attorney, Agent, or Firm* — Brinks Gilson & Lione(57) **CLAIM**

The ornamental design for a transitional handle, as shown and described.

DESCRIPTION

FIG. 1 is a first side elevation view of a transitional handle; FIG. 2 is a first end elevation view of a transitional handle; FIG. 3 is a second end elevation view of a transitional handle; FIG. 4 is a second side elevation view of a transitional handle; FIG. 5 is a bottom plan view of a transitional handle; FIG. 6 is a top plan view of a transitional handle; and, FIG. 7 is a top perspective view of a transitional handle. The ornamental design which is claimed is shown in solid lines in the drawings. Any broken or phantom lines in the drawings form no part of the claimed design.
